UNITED STATES PATENT OFFICE.

LEWIS E. ZERBE, OF FLINT, MICHIGAN.

RESTAURANT EQUIPMENT.

1,081,358.

Specification of Letters Patent.

Patented Dec. 16, 1913.

Application filed October 16, 1912. Serial No. 726,142.

To all whom it may concern:

Be it known that I, LEWIS E. ZERBE, a citizen of the United States of America, residing at Flint, in the county of Genesee and State of Michigan, have invented certain new and useful Improvements in Restaurant Equipment, of which the following is a specification, reference being had therein to the accompanying drawings.

10 This invention relates to a construction and arrangement of devices for facilitating the handling and washing of dishes and clearing and setting the tables in the dining rooms of restaurants and similar eating houses, the same being adapted for very large dining rooms where it is especially desirous to clear the tables with facility.

20 The object of the invention is to provide a suitable arrangement of movable tables and carriers, and means for actuating the same whereby the tables are automatically cleared of dishes and the dishes conveyed to a central point for washing.

25 A further object of the invention is to provide suitable mechanism for actuating the tables and carriers so arranged that they may be actuated in unison and in timed relation or may be separately actuated.

30 A further object of the invention is to provide an arrangement of these devices whereby the same are adapted for installation in a large dining room, and to provide certain other new and useful features, all as herein-after more fully described and pointed out 35 in the claims reference being had to the accompanying drawings in which—

Figure 1 is a diagrammatic view showing the installation and arrangement of devices embodying the invention in plan view; Fig. 40 2 is an enlarged transverse section of the same on the line II—II of Fig. 1; Fig. 3 is a view showing the dish washing apparatus in side elevation and a vertical section through the kitchen portion of the mechanism; Fig. 4 is an enlarged detail showing the driving mechanism and adjacent parts in plan view; Fig. 5 is a longitudinal section through one of the movable tables; Fig. 6 is a transverse section of the same; Fig. 7 is an enlarged detail showing one of the 45 tables in dumping position; and Fig. 8 is a sectional detail of the intermittent gear on the line X—X of Fig. 4.

50 The floor or space within a suitable building is divided by a partition 1 into a dining room at one side of the partition and a

kitchen at the opposite side. This wall or partition is provided with openings 2 and any desired number of rows of movable tables 3 are provided to be moved by suitable mechanism hereinafter described, through the openings in the wall to convey the dishes and remnants of a meal from the dining room into the kitchen. The tables comprising each row are preferably of a length to 60 accommodate four people, two at each side thereof seated upon suitable stools 4 and these tables are placed end to end in a continuous row and guided by means of channel bars 5 secured upon the upper ends of suitable supporting brackets 6 fastened to the floor. The tables are connected by means of a link chain 7 passing beneath them at their longitudinal center, and each table is securely bolted at its transverse center line to 70 a flanged link 8 of the chain to move therewith to and around sprocket wheels 9 which are positioned within the kitchen at the end of each row of tables. These sprocket wheels 9 are secured upon a shaft 10 which 75 is driven in the manner hereinafter described and when the sprockets are turned the chain travels around the sprocket carrying the tables therewith through an opening in the floor 11 and beneath the same. The chain 80 passes over suitable guide pulleys 12 and 13 located at the end of each row of tables opposite that at which the sprocket wheel is positioned and a tightener 14 located beneath the floor is provided to keep a tension 85 on the chain. This chain may comprise a section of sprocket chain which is slightly longer than the length of the row of tables and a section of cable connecting the ends of the link portion of the chain and passing 90 over the pulleys.

95 Located within the kitchen at the end of each row of dining tables is an inclined chute 15 with its lower end supported adjacent to one side and the upper run of a continuous traveling carrier 16 which is preferably formed of a suitable wire netting. The upper run of this traveling carrier or belt rests within a suitable guide trough 17 and the carrier is supported at each end by 100 suitable wheels or sprockets 18 mounted upon transverse shafts 19 and 20 supported in bearings on suitable brackets fastened to the floor.

105 Located midway of the length of the kitchen is a stationary receiving table 21 positioned slightly below the plane of

the upper run of the carrier 16 to receive the articles from the carrier, there being two of these carriers in the kitchen and two receiving tables located adjacent to each other so that the dishes from all of the several rows of dining tables throughout the length of the dining room are conveyed by the carriers 16 to a central point in the kitchen and deposited upon these receiving tables 21 which are positioned a short distance apart and adjacent to a suitable pit 22 in the floor in which the operators stand while picking up and removing the remnants of the meal deposited upon the receiving tables. Within the pit 22 is located a bracket 23 secured to the floor of the pit and provided with bearings at its upper end for shafts upon which are secured two pairs of sprocket wheels 24 engaged by two endless sprocket chains 25 which serve as carriers for a series of baskets 26 into which the dishes from the table 21 are packed by the operators. By suitable driving mechanism to be hereinafter described, the chain is driven and intermittently stopped with two of the baskets carried thereby between the tables 21 with their upper edges substantially in the plane of said tables. When two of the baskets have been filled the chain is moved to bring the next two baskets into place and the filled baskets pass vertically upward, thence horizontally a short distance with the chains engaging idlers 27 to support the chains and the weight of the filled baskets. The baskets travel horizontally to a point directly above a suitable washing tank 28 which is supplied with hot water through a supply pipe 29 and is provided with a discharge outlet 30. The chains then pass vertically downward within this tank over idlers 31 located near the bottom thereof and thus the baskets are immersed in the water contained in the tank and then lifted out and carried horizontally to a point above a second tank 84 in which they are immersed in a like manner, said tanks having a common water supply pipe and like outlets. A third or rinsing tank 32 is supported with its bottom substantially in the plane of the upper ends of the tanks 28 and 84 and the pipe 29 is connected to the outlet at the bottom of this tank so that the hot rinsing water contained in the tank 32 may be let out into the washing tanks to supply the same with washing water. From the tank 84 the chains carry the baskets vertically upward to a point above the tank 32, said chains passing over idlers and thence downward into the tank 32 over idlers 31 the same as in the other tanks and vertically out of the tank again to immerse the baskets and the washed dishes contained therein in very hot water. From the tank 32 the chain passes horizontally for a short distance over suitable idlers and thence vertically down-

ward and around idlers 33 mounted upon a bracket 34 secured to a receiving table 35 where the baskets of clean dishes are disconnected from the chains and empty baskets hung thereon in their place. After passing around the idlers 33 the chain passes vertically upward, thence horizontally over other idlers 27 to a point directly above the sprockets 24 and around said sprockets making a complete circuit and bring empty baskets into position adjacent to the receiving tables 21 to be filled therefrom.

Obviously dish washing mechanism of any suitable construction may be installed and the dishes conveyed thereto by the carriers 25 from the receiving tables 21, the particular mechanism shown in Fig. 3 being to illustrate one form of dish washing mechanism, the same forming no part of this invention.

In order to prevent breakage of dishes it is necessary to move the dining tables in timed relation to the movement of the carriers 16 so that one table of each of the rows of tables will be simultaneously dumped to deposit the dishes thereon through the chute 90 simultaneously upon the carrier 16 and the actuating mechanism for said rows of tables will then stop long enough to permit the dishes so deposited upon the carrier to be conveyed thereby to the receiving table 95 and packed in the baskets before the next table of each row is dumped. It is also necessary to provide suitable mechanism for intermittently actuating the carrier chains 25 to bring the pairs of baskets into position opposite the receiving tables and hold them there a sufficient length of time to permit the operators to fill the baskets with dishes from these tables. An intermittent movement of the carrier chains is also necessary to permit the removal of the filled baskets therefrom and the placing of empty baskets in position. Any suitable mechanism for so actuating the several parts may be provided but as an illustration of such a mechanism the diagrammatic plan view of power transmitting mechanism is shown in Fig. 4. In this figure a suitable electric motor is indicated at 44 for actuating a drive shaft 45 which is provided with a worm 46 to transmit motion therefrom to a worm gear 47 secured upon a shaft 48 extending at right angles thereto and toward the bracket 23 forming the support for the sprocket wheels 24 which engage and drive the carrier chains 25. On the end of this shaft 48 is a sprocket 49 engaged by a suitable sprocket chain for transmitting motion from the shaft to a similar sprocket wheel secured upon a stop shaft 50. The opposite end of the shaft 50 is provided with a sprocket 51 engaged by the sprocket chain for transmitting motion therefrom beneath one of the receiving tables to a sprocket wheel 52 secured upon the end of the shaft 130

20 carrying the wheels 28 over which one of the carriers 16 passes. Sprockets and sprocket chain similar to the sprockets 51 and 52 are provided for driving the other carrier 16 at the opposite side of the dish washing mechanism and motion is transmitted from the shaft 48 to actuate said carrier by means of a gear 53 which is loose upon said shaft engaging a gear 54 secured 10 to the sprocket wheel 51. The hub of the gear 53 is formed with teeth adapted to be engaged by a clutch member 55 splined on the shaft 48. By suitable lever mechanism indicated at 56, the gear 54 may be thrown 15 out of mesh with the gear 53 and thus the carrier driven thereby thrown out of operation. Motion is transmitted from the shaft 48 to drive the sprocket wheels 24 and carrier chains engaged thereby, by a pinion 57 20 on a short shaft 58 which pinion is in engagement with the gear 53. On the end of the shaft 58 is secured one of the sprocket wheels 24 at the inner side of the baskets and a gear 59 is also secured on said shaft 25 adjacent to the sprocket to be engaged by an intermediate gear 60 secured upon a shaft 61 which extends across between the two carrier chains 25 and has a bearing at its outer end in the bracket 23. The other 30 sprocket wheel of the pair 24 which engages the chain at the inner side of the baskets, is provided with a gear 62 in engagement with the gear 60 and thus the sprockets of the pair are driven at the same rate of speed 35 and in the proper direction. The pair of sprocket wheels 24 which are mounted on the bracket 23 to drive the carrier chain at the outer sides of the baskets, are driven by means of a pinion similar to the pinion 60 40 on the shaft 61 engaging gears attached to the sprocket wheels. The two carrier chains 25 are each positively driven by two sprocket wheels and the two pairs of sprocket wheels are so driven that they turn in unison. The 45 transmission of motion from the shaft 48 to drive the carrier chains 25, may be stopped by moving the clutch 55 out of engagement with the gear 53 as shown and this clutch is moved by means of an arm 50 55 secured upon a longitudinally movable shaft 64 and this shaft is moved endwise by means of any suitable lever mechanism 65. The shaft 10 upon which large sprocket wheels 9 are mounted for actuating the dining tables, is turned intermittently in timed 55 relation to the movement of the carriers 16 by means of a mutilated or intermittent gear 66 which transmits motion through intermediate gears 67 and 68 to a gear 69 secured 60 upon said shaft 10. This intermittent gear receives motion from the shaft 48 by means of a beveled gear 70 on the end of the shaft 71 to which the intermittent gear is secured, said beveled gear being in 65 engagement with a like gear 72 secured upon a sleeve 73 on the shaft 48. This sleeve is free to turn upon the shaft but may be directly connected thereto by means of clutch members 74 one of which is secured to the shaft and the other splined to the sleeve to move longitudinally thereof. When the clutch members 74 are engaged motion at a comparatively high speed is transmitted to the shaft 10 to turn the same in a direction which will move the dining 70 tables into the dining room from beneath the floor to which position they have been previously carried in the operation of unloading. A slow motion is transmitted from the shaft 48 to turn the shaft 10 and move 75 the dining tables into the kitchen where they discharge their loads and pass around the sprocket wheels 9 beneath the floor; by providing a counter shaft 75 which is geared to the shaft 48 at one end and is provided with a gear 76 at its opposite end engaged by an idler gear 77 which in turn is engaged by a gear 78 splined upon the sleeve 73 and the hub of which is engaged by a shifting fork 79 secured upon a sleeve 80 movable 80 longitudinally upon the shaft 64. A like forked arm 81 is also secured upon the sleeve to engage the movable member of the clutch 74 and thus when the sleeve 80 is shifted by means of suitable lever mechanism 82, the movable clutch member and the gear 78 will be simultaneously moved, the one into operative position and the other out of operative position. The shaft 10 is 85 preferably made in sections and the sections connected by means of couplings 83 which may be uncoupled when it is desired to operate certain sections of rows of dining tables and thus if the whole dining room is not used it will not be necessary to operate all 90 of the tables when unloading those which have been used. By this arrangement of driving mechanism the dining tables are intermittently operated in timed relation to the movement of the carriers 16 and the dish washing apparatus is also actuated in timed 95 relation to the carriers and the discharge of dishes upon the receiving tables. 100

Obviously, other mechanism may be employed to drive the several parts and operate them in timed relation and the construction, arrangement and relation of the dining tables, carriers and dish washing mechanism may be changed without departing from the spirit of my invention and I do not limit myself to the particular form or construction herein shown and described. 115

Having thus fully described my invention what I claim is:—

1. The combination of a plurality of dining tables arranged end to end in a continuous row and having smooth upper surfaces adapted to support dishes, means for supporting and guiding said tables, means connecting said tables for moving the entire 125

row longitudinally, a rotary member at one end of the row of tables around one side of which the tables are carried by said means, a receiving member adjacent to said rotary member, and power transmitting mechanism for actuating said connecting means and automatically stopping the same as each of the tables reaches a predetermined tilted position to discharge its load upon 10 said receiving member during its travel around said rotary member.

2. The combination of a plurality of dining tables arranged in a continuous row and having an upper surface on which dishes 15 are adapted to be supported, means for connecting said tables and moving the row longitudinally, a rotary member at one end of the row of tables around which the tables pass when moved by said means, an inclined chute, and means for automatically 20 stopping said means for moving the row as each table is tilted in passing around said rotary member into alinement with said chute to discharge its load thereon.

25 3. The combination of a row of dining tables having an upper surface upon which dishes are adapted to be supported, means for supporting and guiding said tables, a rotary member at one end of the row of 30 tables downward around which the tables are adapted to pass, an inclined chute adjacent the rotary member, and means for intermittently actuating the tables to stop each table in alinement with said chute as it 35 travels around the rotary member.

4. The combination of a row of separate dining tables arranged end to end, a chain 40 for actuating the row of tables, to which each table is attached, a rotary member at the end of the row around which the chain passes to move the tables horizontally and carry them downward and beneath said member in an inverted position, means for intermittently operating the chain to stop 45 each table in an inclined position during its travel around the rotary member, and an inclined chute having sides extending at the sides of the tables and a bottom in alinement with the tables when tilted.

50 5. The combination of a plurality of parallel rows of dining tables, a carrier extend-

ing at right angles to said rows adjacent to one end thereof, means at the end of each row for consecutively tilting the tables, one at a time, means for actuating the carrier, 55 and means for intermittently moving the several rows longitudinally.

6. The combination of dining tables arranged end to end in a series of parallel rows, means for simultaneously moving the 60 rows of tables longitudinally, a carrier extending horizontally adjacent to one end of the several rows of tables to receive dishes therefrom, means at said end of each row for consecutively tilting the tables, a power 65 transmitting mechanism for actuating said carrier and moving the several rows of tables longitudinally and intermittently.

7. The combination of a plurality of rows of movable dining tables, a carrier extending horizontally adjacent to the ends of said 70 rows of tables to receive dishes therefrom, means for intermittently moving the rows of tables, a fixed receiving table at one end of the horizontal carrier, and means under 75 the control of the operator for actuating the horizontal carrier.

8. The combination of a plurality of rows of movable dining tables, a carrier extending horizontally adjacent to the ends of said 80 rows of tables to receive dishes therefrom, an upwardly extending carrier adjacent to the end of the horizontal carrier and provided with means for holding dishes, and means for intermittently moving the rows 85 of tables and actuating the carriers.

9. The combination of a plurality of rows of movable dining tables, a carrier extending horizontally adjacent to the ends of said 90 rows of tables to receive dishes therefrom, a fixed receiving table adjacent to the end of said carrier, a vertical carrier adjacent to the fixed table, and means for actuating the horizontal carrier and intermittently moving the rows of tables and the vertical car- 95 rier.

In testimony whereof I affix my signature in presence of two witnesses.

LEWIS E. ZERBE.
